(57) **CLAIM**

The ornamental design for a dustpan, as shown and described.

DESCRIPTION

FIG. 1 is a perspective view showing the new design for a dustpan;

FIG. 2 is a right side view thereof, a left side view being a mirror image thereof;

FIG. 3 is a top view thereof;

FIG. 4 is a front view thereof;

FIG. 5 is a bottom view thereof;

FIG. 6 is a rear view thereof; and,

FIG. 7 is a perspective view thereof showing the dustpan with a handle.

The portions of the dustpan in FIGS. 3, 5, and 7 shown in broken lines are included to show features that form no part of the claimed design.

1 Claim, 4 Drawing Sheets

FIG. 1
